US00D504694S

(12) **United States Design Patent** (10) Patent No.: **US D504,694 S**
Dittmann et al. (45) Date of Patent: ** May 3, 2005

(54) **APPARATUS FOR MELTING AND DISPENSING OF MATERIAL**

(75) Inventors: **Ralf Dittmann**, Melbek (DE); **Harald Meyer**, Betzendorf (DE); **Jirka Trhlik**, Frankfurt (DE); **Kay-Uwe Witte**, Offenbach (DE); **Kai Herda**, Hessen (DE)

(73) Assignee: **Nordson Corporation**, Westlake, OH (US)

(**) Term: **14 Years**

(21) Appl. No.: **29/194,012**

(22) Filed: **Nov. 18, 2003**

Related U.S. Application Data

(62) Division of application No. 29/177,991, filed on Mar. 19, 2003, now Pat. No. Des. 488,177.

(57) **CLAIM**

The ornamental design for an apparatus for melting and dispensing of material, as shown and described.

DESCRIPTION

FIG. 1 is a front perspective view of the apparatus for melting and dispensing of material.

FIG. 2 is a front elevational view of the apparatus for melting and dispensing of material.

FIG. 3 is a right side view of the apparatus for melting and dispensing of material.

FIG. 4 is a rear elevational view of the apparatus for melting and dispensing of material.

FIG. 5 is a left side view of the apparatus for melting and dispensing of material.

FIG. 6 is a top view of the apparatus for melting and dispensing of material; and,

FIG. 7 is a bottom view of the apparatus for melting and dispensing of material.
